James L. Jackson

Design for a Screen for Steam Pikes etc.

No. 1

Patented April 13, 1858.

Dec. 997

James L. Jackson, of New York, N.Y.
Letters Patent, No. 997, dated, Apr. 13, 1858.

The schedule referred to in these Letters Patent and making part of the same

To all whom it may concern:

Be it known that I, James L. Jackson, of the City County and State of New York, have invented or produced a new and original Design for Screens, for Steam pipes or other similar purposes, and that the following is a full, clear and exact description of the same reference being had to the accompanying drawing, making a part thereof.

My design consists in a plate, or platis of open work, in panels - the centers of the panels having a raised openwork escutcheon, which is surrounded with tracery, fruit, and flowers - Its object being for screens, for steam pipes, or other similar purposes.

In the center of the plate longitudinally there is a square panel A, within an outer similar shaped panel B, with volute tracery, a, between them - the ground being open. The inner panel A, has rounded corners, b, with spear heads, c, pointing to a common center. In the center of the inner panel A, there is a raised shield or escutcheon c, filled in with radial arms, d, and scroll work, e, the space between the fillings in being openwork. Between the shield, c, and the head of the panel, is filled in with volute tracery, f, with open ground.

On both sides of the middle panel A, there are oblong square panels D, D, with a concavo-convex central shield E, in them, having radial arms g; the alternate ones of which support a centerpiece h, the intermediate arms between the supporting ones not connecting with the centerpiece. There is an arch F, over the shields E, from the base or spring of which hangs a bunch of grapes, i, i, and between the arch and shield, there is tracery and grape leaves, leaving an open ground. Below this shield, and between it and the head of the panel, there is volute tracery k with open ground.

Outside of the three panels and between them and the outer margin of the plate, there is filled in open diamond work, m.

and volutes, *i.e.*, with open ground). This comprises the front plate of the screen. The ends are made of the same configuration of the panels D. Very plain or ornamental moldings may be used above and below these plates. And the top plate is usually a plain one of iron or marble. But I claim only the configuration of the plates.

At the corners there are pilasters E, with caps, *c.* and a base *b*, and around the shaft of the pilaster there is spirally wound a wreath of roses, buds and leaves all as shown in the drawings.

Having thus fully described and represented the nature and object of my design, What I claim is the configuration of the plates herein represented, for the purpose of a screen for steam pipes and other similar purposes, as represented and explained in the drawings.
